UNITED STATES PATENT OFFICE

160,654

ASH TRAY

Marco Pagano, Buffalo, N. Y., assignor to Ira L. Powsner, Buffalo, N. Y.

Application September 9, 1949, Serial No. 4,922

Term of patent 3½ years

(Cl. D85—2)

To all whom it may concern:

Be it known that I, Marco Pagano, a citizen of the United States, residing at Buffalo, in the county of Erie and State of New York, have invented a new, original, and ornamental Design for an Ash Tray, of which the following is a specification, reference being had to the accompanying drawings, forming a part thereof.

I claim:

The ornamental design for an ash tray, substantially as shown.

MARCO PAGANO.
